UNITED STATES PATENT OFFICE.

COURTLAND E. LEER, OF PARIS, KENTUCKY.

BOOKKEEPING-FILE.

No. 895,031.

Specification of Letters Patent.

Patented Aug. 4, 1908.

Application filed April 15, 1908. Serial No. 427,227.

To all whom it may concern:

Be it known that I, COURTLAND E. LEER, a citizen of the United States, residing at Paris, in the county of Bourbon and State of Kentucky, have invented certain new and useful Improvements in Bookkeeping-Files; and I do hereby declare the following to be a full, clear, and exact description of the invention, such as will enable others skilled in the art to which it appertains to make and use the same.

This invention relates to files to be used in connection with a system of keeping accounts or records of events as they transpire from day to day, such as merchants' credit-accounts, the clinical records of physicians, and bank-checks and notes, or other records which must be kept from day to day.

The objects of the invention are to provide a file in the form of a book that can be easily handled and placed in a safe for security in case of fire, and in which the leaves will open without rubbing and mutilating the accounts in opening, and which shall be compact, light and simple in construction, inexpensive in manufacture and efficient and durable in practical use.

The invention will first be hereinafter more particularly described, with reference to the accompanying drawings, which are to be taken as a part of this specification, and then pointed out in the claims at the end of the description.

In said drawings, Figure 1 represents a plan view of a book-form file embodying my invention, showing the book open in position for making entries or placing therein slips of paper, cards or other papers on which entries have been or may be made; Fig. 2 is an end view of the open file shown in Fig. 1; Fig. 3 is a rear view showing the file closed; Fig. 4 is a perspective view of the file having a cover applied thereto, giving the appearance of an ordinary book; and Fig. 5 is an end view of the file with the leaves thereof folded.

Referring to said drawings, in which the same reference letters are used to denote corresponding parts in different views, the letters A, A, may denote a series of plates or sections forming the leaves of the book-form file, and which are preferably made or stamped out of sheet metal, being rectangular in form and having marginal ribs or flanges a, a on opposite sides thereof, so as to form shallow box-like receptacles, within

which may be placed slips of paper, cards or the like, on which accounts may be kept, or other papers on which entries have been or may be made from day to day. Division 60 plates or partitions B may also be provided upon opposite sides of each section or plate A, so as to divide each side or face thereof into three, more or less, divisions, and in these divisions are placed a series of spring-clips or other securing means. In the form shown an elastic wire or wires are bent so as to form a series of substantially U-shaped springs having coils at their ends which are inserted in apertures in the division plates 70 and marginal flanges of the leaves of the file so as to provide a series of U-shaped spring-clips C in each division, upon opposite sides of the leaf, for holding the paper slips, cards or other records in proper position and to 75 prevent them from dropping out when the file is open.

As will be observed, the leaves are of the same size and are placed one upon or beside another and connected together by suitable 80 hinges so as to adapt the series of leaves to be readily opened and folded like the leaves of a book, the leaves being so positioned that the marginal portions or edges thereof lie in the same or substantially the same vertical 85 or horizontal plane, whether the leaves are open, as illustrated in Figs. 1 and 2, or closed, as illustrated in Figs. 3, 4 and 5. In the form shown, the series of leaves or metallic sections are pivotally connected together 90 by strap-hinges D of different lengths, which may have eyes at one end fitted upon a connecting rod E while the butt ends of each pair of hinges are secured to one of a series of leaves lying one upon or beside another as 95 shown. Short hinges are used to connect the two inner or middle leaves of the series close to the connecting rod E and longer hinges are used to connect the outer leaves successively, the length of the hinge varying 100 in proportion to the distance the leaf to which it is attached is removed from the connecting rod, so that an equal number of leaves may be arranged upon opposite sides of the rod or axis of the hinge and adapted to 105 lie one upon another with their marginal portions or edges in the same vertical plane when the file is open in position for use, as shown in Figs. 1 and 2 of the drawings. To counteract a tendency on the part of the leaves, especially the outer leaves, to "crawl" 110 or slide upon the adjacent leaves, I prefer-

ably make the hinges which connect the two outer leaves of substantially L-shaped form, so that one limb thereof extends from the axis of the hinge in a plane substantially parallel with the two innermost or middle leaves, while the other limb extends substantially at right angles to the entire group, thus forming an abutment for the rear edges of the leaves which will prevent crawling or 10 sliding one upon another, with consequent disfiguring or mutilation of the records contained within the file:

In order to give the file the appearance of a book, a metallic cover F, in the form of an ordinary book-cover having back f' and hinged sides f' may be provided for inclosing the group of leaves constituting the file, or the outer leaves may have plain outer sides and a suitable back like that of a book-cover 20 secured thereto, if desired, thus giving the general appearance of an ordinary book.

This file is designed to be used with a system of keeping accounts which may be briefly explained thus: The spaces for the 25 accounts are all numbered on the various leaves, the numbers corresponding to numbers in an index on the inside of the first or outer leaf, each customer having a certain number. As the accounts, etc. are filed the 30 record may be carried forward on each account, thereby saving considerable time in looking over all the accounts pertaining to one customer. The same principle applies to the clinical records of physicians' and 35 bankers' checks. The indebtedness of a customer or a depositor's balance can be seen at once by opening the file to the number corresponding to the name in the index, the amount having been carried forward 40 appearing on the top account.

I am aware that prior to my invention files of the same general character have been used, and hence I make no broad claim to such contrivances, but the devices heretofore used are more or less complex and expensive in manufacture and also objectionable in use, because of the rubbing or crawling of the leaves one upon another in opening and closing the book, with consequent tearing or mutilation of the records secured 50 therein.

Having thus described my invention, what I claim as new and desire to secure by Letters Patent of the United States is:

55 1. A credit account file in book form comprising a series of leaf-like plates hinged upon a common connecting rod which extends parallel with and midway of the entire series of

plates when folded like a book, the hinges being constructed in different lengths with 60 each pair thereof at each side of said rod of greater length than the next preceding pair in the series, said plates being adapted to be opened so as to lie in two groups arranged upon opposite sides of said connecting rod 65 with their marginal portions or edges in substantially the same plane, and means for holding slips of paper, cards or the like on the faces of said plates.

2. A book-form file comprising a series of 70 leaf-like plates hinged together in book form and having the axes of their hinges arranged in a plane parallel with and midway of the entire series when folded, said hinges being of different lengths and increasing in length 75 successively at each side of said hinged connections from the innermost to the outermost leaf of the book, whereby said plates are adapted to lie as an open book in two groups on opposite sides of the hinged connections with the marginal portions of each group in the same vertical plane, and means for holding slips of paper, cards or the like on the faces of said plates.

3. A book-form file comprising a series of 85 leaf-like plates hinged together so as to adapt them to be folded like the leaves of a book and when opened to lie in two groups arranged upon opposite sides of their hinged connections, the hinges being of different 90 lengths and those of the outer plates being constructed and adapted to serve as abutments for the intermediate plates to prevent "crawling" or sliding movement of the plates 95 one upon another.

4. A book-form file comprising a series of rigid leaves or plates hinged together so as to be folded like the leaves of a book, and having means for holding slips of paper or the like 100 on their faces, the two innermost leaves being connected by short hinges and the other leaves being connected successively by hinges each pair of which is of greater length than the next preceding pair in the series, the hinges of the two outermost side leaves 105 being substantially L-shaped so as to provide abutments for the intermediate leaves and prevent "crawling" or sliding movement of the leaves with consequent rubbing and mutilation of records therebetween.

11 In testimony whereof I affix my signature, in presence of two witnesses.

COURTLAND E. LEER.
